(57) **CLAIM**

The ornamental design for a handheld ultrasonic thickness testing and measuring device, as shown and described.

DESCRIPTION

FIG. 1 is a front view of a handheld ultrasonic thickness testing and measuring device showing our new design;

FIG. 2 is a rear view thereof;

FIG. 3 is a top view thereof;

FIG. 4 is a bottom view thereof;

FIG. 5 is a right side view thereof;

FIG. 6 is a left side view thereof; and,

FIG. 7 is a perspective view thereof.

The broken lines in FIGS. 2-7 are for illustrative purposes only and form no part of the claimed design.
